SEPARATOR

Henry H. Logan, Chicago, Ill., assignor to Logan
Engineering Co., Chicago, Ill., a corporation
of Illinois

Application July 31, 1936, Serial No. 93,625
Renewed November 26, 1937

18 Claims. (Cl. 183—77)

The present invention relates to separators and is particularly concerned with devices which are adapted to separate liquids from gases.

Compressed air usually contains moisture, as moisture is carried in free air, and as the air is compressed the amount of moisture per unit volume is increased. As the volume of the air is reduced, the relative humidity of the air increases and the moisture in the air bears a larger ratio to the volume of the air than it would have before the air was compressed.

Such moisture in the air causes piping to rust, and in cold weather it frequently causes the air pipes to freeze and stop the air flow, the moisture gradually cooling on the inner surfaces of the pipes and freezing until the pipes become entirely closed by ice.

In many operations where compressed air is used, such as in paint spraying, water causes damage to the paint job. When the air is used for sand blasting, it tends to cause the sand to cake and to interfere with the efficiency of the sand blasting process. When the "sand blasting" is done with air and steel shot, which is desirable for some purposes, moisture causes the shot to rust which damages the work being done.

When compressed air is used to blow dust, cuttings, etc., from machines, it should also be perfectly dry for otherwise it will tend to cause the parts of the machine to rust. Compressed air also usually carries a certain amount of oil picked up from the air compressor cylinder, which, of course, must be lubricated.

When air is used for such purposes as refining oil for human use, forcing milk out of tank cars or other similar purposes to which it is frequently put, it is obvious that it should be free from foreign matter, such as water, oil, dust particles, or the like.

One of the objects of the invention is the provision of an improved separator which is adapted to separate from air or other gas such foreign matters as water, oil, other liquids, or the like.

Another object of the invention is the provision of an improved separator which is highly efficient in operation, economical to install, small in size, and which has all of its parts accessible for inspection or repair.

Another object of the invention is the provision of an improved unit assembly in which all of the moving parts are secured to a single member so that they may be removed from the housing as a unit for inspection and repair, and so that when the housing is placed over them and fastened the assembly is completed.

Other objects and advantages of the invention will be apparent from the following description and accompanying drawing in which similar characters of reference indicate similar parts throughout the several views.

Referring to the single sheet of drawings, Fig. 1 is an elevational view of a separator constructed according to the present invention;

Fig. 2 is a vertical sectional view taken on a plane passing through the axis of the intake and discharge apertures of the housing, which are centrally located;

Fig. 3 is a transverse sectional plane taken on the plane of the line 3—3 of Fig. 2 looking in the direction of the arrows; and

Fig. 4 is a fragmentary vertical sectional view taken on the plane of the line 4—4 of Fig. 3 looking in the direction of the arrows and showing the shape of the blades.

Referring to Figs. 1 and 2, the separator, which is indicated in its entirety by the numeral 10, is preferably provided with a housing 11 which may be constructed of cast metal and which may be cylindrical in shape, provided with one closed end 12 having a centrally located discharge port 13 which is threaded to receive a discharge pipe 14. The opposite end of the housing is open, but is provided with a cover 15 forming a part of a base member 16. The cover 15 may have an annular shoulder 17 which is adapted to fit in a cylindrical wall 18 of the housing 11. The cover 15 also has a flat surface engaging the end surface of the housing, to which it is secured by a plurality of cap screws 19 passing through the cover and threaded into the housing wall. The cover and housing may be finished to a water-tight fit or they may be provided with a suitable gasket.

The base 16, which comprises the cover 15, has an upwardly extending conduit 20 centrally located and provided with a threaded intake port 21 adapted to receive an intake pipe 22. The conduit 20 extends upward in the housing 11 and also forms a standard for supporting the moving parts of the separator. Conduit 20 is formed with an enlargement 23 at its upper end and with a radially extending baffle flange 24. The bore 25 in the conduit 20 communicates with a plurality of arcuate ports 26 located about a supporting hub 27 which is carried by a plurality of integral inwardly extending lugs 28. The hub 27 has a central vertical bore 29 for receiving an assembly bolt 30 which is provided with a nut 31. The assembly bolt 30 supports a cap 32 and a plurality of anti-friction bearings 33 by means of supporting the inner races of these bearings.

Each of the bearings is identical and, therefore, only one need be described and each includes a plurality of balls 34, an inner race 35 and an outer race 36. The inner race 35 has a bore 37 which slidably engages the bolt 38. Spacing members 38 and 39 are interposed between the inner races 35 on the bolt 38 and the cap 32 has a centrally located hub 40 with a bore 41, receiving bolt 38. The bolt 38 clamps all of the races 35, spacers 38 and 39 and hubs 27 and 40 together, and the other parts of the bearings, such as the balls 34 and races 36, are suitably held in place by their engagement with their respective inner races. The anti-friction bearings 34-36 support a plurality of rotors 42-45 which may be identical in construction, except that two of the rotors are preferably right-hand rotors and the other two left-hand rotors. The rotors are alternately disposed so that if the lowermost rotor 45 is a right-hand rotor, then number 44 is left-hand, number 43 right-hand and 42 left-hand. Each of these rotors comprises a cast metal member having a centrally located hub 46 comprising a tubular member of sufficient length to span two of the outer races 36 and a spacer 38. The hub 46 has a pair of aligned bores 47, 48 of the same size, separated by a rib 49 which is engaged between the two races 36 to locate the rotor definitely with respect to its ball-bearings. The rib 49 is of the same thickness as the spacer 38 between two bearings for each rotor.

Hub 46 supports a plurality (in this case seven) of radial and diagonally extending blades 51-53. The blades are defined by the circular outer line 50, the circular inner line 51 and the two diverging lines 52, 53 in Fig. 3. Their pitch is shown in Fig. 4. The blades on each rotor slope in the same direction, and obviously the blades on the right-hand rotors slope in the opposite direction to those on the left-hand rotors.

The slots 54 between the blades are defined by the trailing edge 55 and the leading edge 56 of adjacent blades. The blades 51-53 support at their peripheries a baffle 64 which is preferably substantially frusto-conical in shape and of greater length than the hub 46, so that the baffles 64 overlap each other. The taper of the baffles 64 is such that the baffles on one rotor at the small end may be received in the larger end of the baffles of the next rotor, leaving a slight clearance 65 between them to permit moisture to run down the surfaces of the baffle. Each baffle 64 may be provided with one or more drilled apertures 66 located just above the outer surface 55 of each blade at the center of the blade, that is, midway between the edges 52, 53, to permit liquid to drain to the outer surface of the baffles 64. The lowermost baffle 64 receives and overlaps the radial extending flange 24 on the standard 20, which has a frusto-conical surface 67 like the outside of a baffle.

The cap 32 is preferably provided with a cylindrical flange 68 secured to the hub 69 by a plurality of integral struts 70. The cylindrical flange 68 fits in a bore 71 in a tubular extension 72 of the housing 11 leading to the discharge port 13. The cap 32 also has a radially extending flange 73 formed with a downwardly extending border flange 74 having an inner surface 75 which is frusto-conical, like the lower inside of a baffle 64, fitting over the topmost rotor 42 in a manner similar to the fit between adjacent rotors, that is, closely spaced but without contact. The radial flange 73 may have a plurality of ripples or ribs 76 located on its lower surface increasing the resist-

ance to the path of the air leaking around the outside of the rotors and causing the air to pass through the rotors rather than around the outside and in between the uppermost rotor and the cap 32.

It will be thus observed that the bearings are locked in place and the rotors are held in proper position by the annular ring on each rotor which engages between two bearings. Each bearing may be provided with a shield on the outside so that the center space between adjoining bearings may be packed with grease for lubrication, and all of the moving parts may be removed as a unit since they are all supported by the standard 18.

The operation of the device is as follows: The air passing upward through the intake port 21 causes the rotors to revolve, the blades of which cut across the air stream. As the particles of oil or moisture come into contact with the rapidly revolving blades, these particles are thrown outward by centrifugal force until deflected by the conical rim, from which they are thrown in a downward direction dropping into the base chamber 11. From this chamber they are drained off by a trap which is connected with the liquid outlet 78, the trap preferably being of the type which opens when liquid rises in it, but which closes and prevents air from escaping when the liquid has been drained off. The resistance to the passage of air outside of the rotors is greater than the resistance passing through the rotors and, therefore, the air or the major part of it passes through the rotors and causes them to revolve.

The housing 11 is preferably provided with a boss 80 adjacent its lower part in one of its side walls, the boss being provided with a relatively large tapped threaded bore 81. The bore 81 may be closed by a threaded clean-out plug, and the opening 81 may be used for observation of the parts or for cleaning out the separator housing by means of a blast of air or by the attachment of the water hose, the sediment, etc., being discharged through the usual discharge port for liquid. Of course, during the clean-out operation by means of compressed air or water the intake and output lines of the separator are shut off by appropriate valves.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In a separator, the combination of a housing with a cover plate, said cover plate having a standard and a plurality of rotors, each rotor having blades adapted to be engaged by a fluid medium to impel the rotors into rotation whereby liquid in the fluid medium is engaged by the blades of the rotors and thrown off centrifugally, said rotors and cover plate being removable as a unit, said rotors being provided with a peripheral band adapted to act as a baffle to deflect liquid downward and outward, said baffles being frusto-conical in shape and overlapping baffles on adjacent rotors.

2. In a separator, the combination of a housing with a cover plate, said cover plate having a standard and a plurality of rotors, each rotor having blades adapted to be engaged by a fluid medium to impel the rotors into rotation where-

- by liquid in the fluid medium is engaged by the blades of the rotors and thrown off centrifugally, said rotors and cover plate being removable as a unit, said rotors being provided with a peripheral band adapted to act as a baffle to deflect liquid downward and outward, said baffles being frustoconical in shape and overlapping baffles on adjacent rotors, said rotors being alternately arranged for opposite rotation.
3. In a separator, the combination of a housing with a cover plate, said cover plate having a standard and a plurality of rotors, each rotor having blades adapted to be engaged by a fluid medium to impel the rotors into rotation whereby liquid in the fluid medium is engaged by the blades of the rotors and thrown off centrifugally, said rotors and cover plate being removable as a unit, said rotors being provided with a peripheral band adapted to act as a baffle to deflect liquid downward and outward, said baffles being frustoconical in shape and overlapping baffles on adjacent rotors, said rotors being alternately arranged for opposite rotation, and each rotor being supported on a pair of anti-friction bearings.
4. In a separator, the combination of a housing with a cover plate, said cover plate having a standard and a plurality of rotors, each rotor having blades adapted to be engaged by a fluid medium to impel the rotors into rotation whereby liquid in the fluid medium is engaged by the blades of the rotors and thrown off centrifugally, said rotors and cover plate being removable as a unit, said rotors being provided with a peripheral band adapted to act as a baffle to deflect liquid downward and outward, said band projecting above the blades and said peripheral band being provided with drainage apertures above the blades.
5. In a liquid separator, the combination of a housing provided with means for supporting in the housing a plurality of rotors, said housing having an inlet port at one side of said rotors and an outlet port at the opposite side of said rotors, and said rotors substantially filling said housing so that a fluid medium passing from said inlet port to said outlet port is compelled to pass through said rotors, each rotor having a plurality of blades inclined with respect to the direction of motion of the fluid medium, whereby the rotors are adapted to be rotated by the fluid medium, each of said rotors having a peripherally extending annular band, and said bands on adjacent rotors overlapping each other, for the purpose of minimizing the egress of fluid medium as such from the edges of said rotors, whereby liquid in the fluid medium is engaged by the blades of said rotors and directed to said peripheral bands and discharged from the edges of said peripheral bands.
6. In a liquid separator, the combination of a housing provided with means for supporting in the housing a plurality of rotors, said housing having an inlet port at one side of said rotors and an outlet port at the opposite side of said rotors, and said rotors substantially filling said housing so that a fluid medium passing from said inlet port to said outlet port is compelled to pass through said rotors, each rotor having a plurality of blades inclined with respect to the direction of motion of the fluid medium, whereby the rotors are adapted to be rotated by the fluid medium, each of said rotors having a peripherally extending annular band, and said bands on adjacent rotors overlapping each other, for the purpose of minimizing the egress of fluid medium as such from the edges of said rotors, whereby liquid in the fluid medium is engaged by the blades of said rotors and directed to said peripheral bands and discharged from the edges of said peripheral bands, the adjacent rotors having their blades sloping in opposite directions, whereby adjacent rotors are arranged to rotate in opposite directions, to increase the random contact of fluid medium with the blades of said rotors.
7. In a liquid separator, the combination of a housing provided with means for supporting in the housing a plurality of rotors, said housing having an inlet port at one side of said rotors and an outlet port at the opposite side of said rotors, and said rotors substantially filling said housing so that a fluid medium passing from said inlet port to said outlet port is compelled to pass through said rotors, each rotor having a plurality of blades inclined with respect to the direction of motion of the fluid medium, whereby the rotors are adapted to be rotated by the fluid medium, each of said rotors having a peripherally extending annular band, and said bands on adjacent rotors overlapping each other, for the purpose of minimizing the egress of fluid medium as such from the edges of said rotors, whereby liquid in the fluid medium is engaged by the blades of said rotors and directed to said peripheral bands and discharged from the edges of said peripheral bands, said overlapping peripheral bands extending downwardly and outwardly for directing the course of liquid separated from the fluid medium by means of centrifugal force.
8. In a liquid separator, the combination of a housing provided with means for supporting in the housing a plurality of rotors, said housing having an inlet port at one side of said rotors and an outlet port at the opposite side of said rotors, and said rotors substantially filling said housing so that a fluid medium passing from said inlet port to said outlet port is compelled to pass through said rotors, each rotor having a plurality of blades inclined with respect to the direction of motion of the fluid medium, whereby the rotors are adapted to be rotated by the fluid medium, each of said rotors having a peripherally extending annular band, and said bands on adjacent rotors overlapping each other, for the purpose of minimizing the egress of fluid medium as such from the edges of said rotors, whereby liquid in the fluid medium is engaged by the blades of said rotors and directed to said peripheral bands and discharged from the edges of said peripheral bands, said rotors being supported upon a standard formed with one of said ports and provided with a conduit leading thereto.
9. In a liquid separator, the combination of a housing provided with means for supporting in the housing a plurality of rotors, said housing having an inlet port at one side of said rotors and an outlet port at the opposite side of said rotors, and said rotors substantially filling said housing so that a fluid medium passing from said inlet port to said outlet port is compelled to pass through said rotors, each rotor having a plurality of blades inclined with respect to the direction of motion of the fluid medium, whereby the rotors are adapted to be rotated by the fluid medium, each of said rotors having a peripherally extending annular band, and said bands on adjacent rotors overlapping each other, for the purpose of minimizing the egress of fluid medium as such from the edges of said rotors, whereby liquid in the fluid medium is engaged

by the blades of said rotors and directed to said peripheral bands and discharged from the edges of said peripheral bands, each of said rotors being mounted upon a pair of spaced, anti-friction bearings.

6. 10. In a separator, the combination of a housing having an inlet passage at one end and an outlet passage at the opposite end and having a portion removable to provide access to the interior of the housing, and a series of rotors disposed within the housing, said rotors being provided with blades to cause their rotation by the passage of fluid through the housing, and said rotors being mounted on anti-friction bearings 15 having their stationary members fastened in such a manner that they may be supported by a part of the housing and secured by a bolt passing through the center of the rotors, and having a cap member clamped with the bearings by said bolt, said cap member provided with openings 20 through which the fluid may pass, and having a series of baffles, and a skirt surrounding a portion of the adjacent rotor, the baffles and skirt being provided to arrest any liquid that may be 25 carried past the outer edges of the rotors.

11. In a separator, the combination of a housing having an inlet passage at one end and an outlet passage at the opposite end, with provision for access to the interior of the housing, with 30 a unit comprising a series of rotors arranged to rotate on bearings secured to a part of the housing by means of a central bolt, said central bolt also securing in fixed relation to the part of the housing to which the central bolt is attached, a circular member provided with baffles 35 to arrest liquid that may be carried past the periphery of the rotors, said circular member having a projection fitting a portion of the housing, and arranged to steady the bearings of the rotors, and to permit the assembly or disassembly 40 of the housing without interfering with the assembly of the rotors and bearings.

12. In a liquid separator, the combination of a housing forming a separator chamber, said housing having a fluid inlet, a fluid outlet, and a liquid drain outlet, with a separator unit comprising a supporting bolt and a plurality of rotary impellers, said impellers having laterally sloping and radially extending blades adapted to be engaged by fluid passing through said chamber and through said impellers to cause said impellers to rotate, said impellers being provided with peripherally extending baffles at the ends of said blades, and said baffles being adapted to overlap baffles on adjacent impellers without contact between said baffles.

13. In a liquid separator, the combination of a housing forming a separator chamber, said housing having a fluid inlet, a fluid outlet, and a liquid drain outlet, with a separator unit comprising a supporting bolt and a plurality of rotary impellers, said impellers having laterally sloping and radially extending blades adapted to be engaged by fluid passing through said chamber and through said impellers to cause said impellers to rotate, said impellers being provided with peripherally extending baffles at the ends of said blades, said baffles being adapted to overlap baffles on adjacent impellers without contact between said baffles, each of said impellers being provided with a supporting hub having a bore surrounding said bolt, and said bore having inwardly extending shoulders and anti-friction self-aligning bearings located on each side of

said shoulders for each impeller for rotatably mounting said impellers on said bolt.

14. In a liquid separator, the combination of a housing forming a separator chamber, said housing having a fluid inlet, a fluid outlet, and a liquid drain outlet, with a separator unit comprising a supporting bolt and a plurality of rotary impellers, said impellers having laterally sloping and radially extending blades adapted to be engaged by fluid passing through said chamber and through said impellers to cause said impellers to rotate, said impellers being provided with peripherally extending baffles at the ends of said blades, and said baffles being adapted to overlap baffles on adjacent impellers without contact between said baffles, said bolt being carried by one of the walls of said chamber, said latter wall forming a closure for said chamber.

15. In a liquid separator, the combination of a housing forming a separator chamber, said housing having a fluid inlet, a fluid outlet, and a liquid drain outlet, with a separator unit comprising a supporting bolt and a plurality of rotary impellers, said impellers having laterally sloping and radially extending blades adapted to be engaged by fluid passing through said chamber and through said impellers to cause said impellers to rotate, said impellers being provided with peripherally extending baffles at the ends of said blades, and said baffles being adapted to overlap baffles on adjacent impellers without contact between said baffles, said bolt being carried by one of the walls of said chamber, said latter wall forming a closure for said chamber.

16. In a liquid separator, the combination of a housing forming a separator chamber, said housing having a fluid inlet, a fluid outlet, and a liquid drain outlet, with a separator unit comprising a supporting bolt and a plurality of rotary impellers, said impellers having laterally sloping and radially extending blades adapted to be engaged by fluid passing through said chamber and through said impellers to cause said impellers to rotate, said impellers being provided with peripherally extending baffles at the ends of said blades, and said baffles being adapted to overlap baffles on adjacent impellers without contact between said baffles, said bolt also carrying a cap member provided with apertures for passage of the fluid, and said cap member extending over the blade of the adjacent impeller and having a baffle overlapping the baffle of said adjacent impeller.

17. In a liquid separator, the combination of a housing forming a separator chamber, said housing having a fluid inlet, a fluid outlet, and a liquid drain outlet, with a separator unit comprising a supporting bolt and a plurality of rotary impellers, said impellers having laterally sloping and radially extending blades adapted to be engaged by fluid passing through said chamber and through said impellers to cause said impellers to rotate, said impellers being provided with peripherally extending baffles at the ends of said blades, said baffles being adapted to overlap baffles on adjacent impellers without contact between said baffles, said bolt also carrying a cap member provided with apertures for passage of the fluid, and said cap member extending over the blade of the adjacent impeller and having a baffle overlapping the baffle of said adjacent impeller.

the fluid, said cap member extending over the blade of the adjacent impeller and having a baffle overlapping the baffle of said adjacent impeller, said housing having a bore, and said cap having a sleeve fitting in said bore for supporting that end of the impeller unit.

18. In a liquid separator, the combination of a housing forming a separator chamber, said housing having a fluid inlet, a fluid outlet, and a liquid drain outlet, with a separator unit comprising a supporting bolt and a plurality of rotary impellers, said impellers having laterally sloping and radially extending blades adapted to be engaged by fluid passing through said chamber.

ber to cause rotation of said impellers, anti-friction bearings for mounting said impellers on said bolt and spacing said impellers from each other, said chamber having one of its walls in the form of a closure provided with a conduit, said conduit having a plurality of branches about a central supporting lug, said bolt being carried by said lug, and a cap member at the other end of said bolt provided with through apertures, said cap member having an alignment sleeve fitting in a complementary bore in said chamber to support the opposite end of said separator unit.

HENRY H. LOGAN.
